CLAIM

The ornamental design for a spindlescase attachment for
tapping machines to change the rotation of the tool,
substantially as shown.

DESCRIPTION

FIG. 1 is a front elevational view of a spindlescase at-
tachment for tapping machines to change the rotation of
the tool incorporating my new design;

FIG. 2 is a side elevational view taken from the left of
FIG. 1;

FIG. 3 is a bottom plan view thereof;

FIG. 4 is a rear elevational view thereof;

FIG. 5 is a side elevational view taken from the right of
FIG. 1; and

FIG. 6 is a top plan view thereof.

FIG. 1
